UNITED STATES PATENT OFFICE

FRED J. MEAD, OF EAST ORANGE, NEW JERSEY

GREENHOUSE BED

Application filed September 21, 1925. Serial No. 57,496.

This invention relates to a greenhouse bed, especially adapted for hothouse purposes, which can be very readily and conveniently installed and can also be disassembled with-
5 cut difficulty. It relates especially to a de-
vice of this character that is made up of parts
which can be manufactured in quantity with-
out requiring an inordinate amount of equip-
ment, as the parts which make up the bed
10 partake of only a small variety of shapes that
can be manufactured wherever convenient
and shipped in a disassembled condition.

In carrying out this invention, the parts
that make up the greenhouse bed can be rap-
15 idly assembled in such a manner that they
will be securely held together and danger of
spreading or getting out of position will be
avoided. At the same time the bed in which
plants or the like may be started, is rendered
20 rodent and vermin proof, the bed is economi-
cal of space, air may be excluded from enter-
ing the sides thereof, the bed can be heated
in such a manner that the proper condition
25 of warmth and moisture can be maintained,
and the bed may be changed into a greenhouse
bench with very little trouble.

My invention will be understood from the
description in connection with the accom-
30 panying drawings, in which Fig. 1 is a per-
spective view of an illustrated embodiment
of the invention; Fig. 2 is a sectional end
view of the same; Fig. 3 is a plan view of one
35 of the parts; Fig. 4 is a longitudinal section
of a modification; and Fig. 5 is a horizontal
section along the line 5—5 of Fig. 4.

In the drawings, reference character 10
40 indicates a post which may be made of rein-
forced concrete. This post is rectangular in
cross section and is provided with longitudi-
nal grooves 12 that are preferably flaring
45 outwardly on opposite sides of the posts and
the other sides are made with flat faces, as
indicated at 11. The grooves 12 extend from
one end and terminate at 13 short of the other
end at such a distance as to indicate the proper
50 depth to which the posts are to be imbedded
in the ground. The posts are reinforced by
means of metal rods 14 and may be used both
as side posts and as corner posts, two of the
55 same preferably being used in proper assem-

bled relation, that is, with the grooved side
of one contacting with the smooth or un-
grooved side of the other, to form the corners
of the bed. The posts which are placed along
the sides of the bed are provided with metal
55 supports 15 for heating pipes 26. These sup-
ports may be imbedded in the concrete as the
posts are being formed so that the bifurcated
portions 16 extend on either side of the rein-
forcing rods 14, as shown in Fig. 3.

Boards 20 which may be made of any ap-
propriate material, preferably reinforced
concrete, form the sides and ends of the bed,
as shown in Fig. 1, extending from a groove
12 in one post 10 to a groove 12 in an adj-
60 acent post. These boards 20 when made of
concrete are reinforced by reinforcing rods
21 and the boards are preferably provided
with bevelled edges, as shown at 22, although
the topmost boards of the bed may be made
65 with their upper edges square.

In installing the posts it would be prefer-
able to install the same in blocks of concrete
23, which are imbedded in the earth 24 at
sufficient depth to permit the lower ends of
grooves 12 and the lower edges of the boards
70 20 to extend sufficiently below the surface of
the earth to prevent rodents or vermin from
entering. The beds may be made as long as
desired by installing posts 10 and the boards
20 in line with each other, and the width of
75 the bed may likewise be varied. Although the
bed illustrated is shown as being rectangular,
it is obvious that the beds may be made in
other polygonal shapes in a similar manner,
80 as flaring grooves 12 permit the boards 20 to
be assembled in relation to the posts 10 at
angles other than a right angle. By instal-
ling the pipes 26, as indicated in the draw-
ings and passing heating fluid therethrough,
85 the beds can be kept warm, and as the pipes
do not contact with the side walls, danger of
over-heating is obviated. By having the
edges of the boards 20 below the surface of
the earth and having their beveled edges fit-
90 ting together as indicated in the drawings,
air can be prevented from entering and dry-
ing out the moisture too rapidly.

In the modification shown in Figs. 4 and
95 5, the bed is made so that a sloping roof can
100

be laid on the top thereof and a glass top can be used for admitting heat from the sunshine and retaining the same in the bed. In this modification the posts 10' are preferably 5 made with their tops sloping slightly, the posts for one end of the bed being made longer than those for the other end. A frame 28 for the glass 29 is installed along the top side of the bed, as shown, the side walls having been 10 made by first providing forms extending between posts on the side and pouring concrete in these forms, this concrete being shown at 30. Earth or equivalent material 31 may be introduced into the space left by one of the 15 grooves where two posts come together at a corner.

The bed can be converted into a greenhouse bench elevated above the ground simply by placing beams across the tops of the posts and 20 laying on bottom slabs and side slabs as shown in my prior Patent No. 1,296,684. This is sometimes desirable when the user desires to change from plants that are grown in beds to plants that are grown on benches somewhat elevated above the ground. In making 25 this change, the side pieces of the bed can be used as bottom pieces of the elevated bench.

Instead of placing beams across the top of the pieces as just described to make green 30 house benches, beams may rest upon shoulders provided along one side of the posts at the proper height from the ground, or the beams may simply rest upon blocks to raise them above the ground. The side walls of 35 the benches can be made by retaining the side boards in the grooves in the posts with a small block of proper length resting in the lower portions of the groove to retain the side pieces at the proper height. In this way, 40 good drainage and circulation under the full length of the bench can be obtained.

In case it is desirable to conduct heat to the lower side of the bench this may be done by removing a side board near the bottom of the 45 bench thus making an opening into which the heat can pass. By removing boards on both sides of the bench opposite each other, a draft of hot air can be caused to pass through the soil in the bench. The upper boards can be held in position by blocks in the lower portion 50 of the groove as above described.

It will be evident from the description that a green house bed made according to this invention can be used at a great saving in time, 55 material and space. The side and end walls being made of reinforced concrete can be made thin, thereby saving material, and they can be slipped in and out of place very readily. By having the walls thin more space is 60 left for plants. By previously making the pieces and having the same ready to be assembled, the bed can be constructed very much more readily than if it were necessary to pour the concrete and wait for the same to harden. 65 Solid beds of concrete that are poured in situ

have to be destroyed when taken up, while the pieces from the torn up bed made in accordance with the present invention can be used again.

The posts may be made longer than necessary so as to extend above the sides of the bed of usual depth, so that whenever it is desired to increase the depth, the user can insert more boards in place in the grooves of the posts and then fill the bed with soil to the proper depth.

Changes may be made in the details of construction and in the arrangement of the parts above described without departing from the spirit of my invention.

I claim:

In a polygonal framework, a set of similar posts having longitudinal grooves along opposite sides thereof, a set of duplicate boards, some of said posts being installed with the grooved side of one in contact with an un-grooved side of another one and with others spaced apart with the grooves of successive posts facing each other, said boards extending from the groove of one post to that of another.
